Primary Examiner — Susan Bennett Hattan*Assistant Examiner* — Marie Fast Horse(74) *Attorney, Agent, or Firm* — Renner, Otto, Biosselle & Sklar, LLP**CLAIM**

The ornamental design for a display portion of watch shaped communications equipment, as shown and described.

DESCRIPTION

FIG. 1 is a perspective view of a display portion of watch shaped communications equipment showing my new design;

FIG. 2 is a front view thereof.

FIG. 3 is a rear view thereof.

FIG. 4 is a left side view thereof.

FIG. 5 is a bottom view thereof.

FIG. 6 is a right side view thereof; and,

FIG. 7 is a top view thereof.

The broken lines in FIGS. 1, 4, 5, 6, and 7 depict parts of the display portion of watch shaped communications equipment that form no part of the claim.
